CLOCK DIAL

Roman J. Szalek, La Salle, Ill., assignor to General
Time Corporation, Thomaston, Conn.

Filed Dec. 19, 1974, Ser. No. 534,645

Term of patent 14 years

Int. Cl. D10—07

U.S. Cl. D10—126

The sole figure is a front elevational view showing my new design. The clock dial is conventionally of no appreciable thickness so only this front elevational view is shown.

I claim:

The ornamental design for a clock dial, substantially as shown and described.
